DESK

Russel Wright, New York, N. Y., assignor to Shwayder Brothers, Ecorse, Mich., a corporation of Colorado

Application February 24, 1955, Serial No. 34,658

Term of patent 14 years

(Cl. D33—11)

Fig. 1 is a perspective view of a desk showing my new design;

Fig. 2 is an enlarged fragmentary view in front elevation of the upper portion of the desk; and

Fig. 3 is an enlarged side elevational view thereof with the legs broken away for convenience of illustration only.

I claim:

The ornamental design for a desk, substantially as shown.
